UNITED STATES PATENT OFFICE.

EDWARD W. RATHBUN, OF DESERONTO, ONTARIO, CANADA.

AUTOMATIC APPARATUS FOR CARBONIZING SAWDUST AND PRODUCTION OF GAS.

SPECIFICATION forming part of Letters Patent No. 353,966, dated December 7, 1886.

Application filed January 2, 1885. Serial No. 151,864. (No model.)

To all whom it may concern:

Be it known that I, EDWARD W. RATHBUN, of Deseronto, in the Province of Ontario, Dominion of Canada, have invented new and useful Improvements in Automatic Apparatus for Carbonizing Sawdust and the Production of Gas, of which the following is a specification.

My invention relates to apparatus for the production of gas from sawdust for illuminating, heating, and other purposes, working, as nearly as may be, automatically, and relates more particularly to the apparatus known as "Halliday's Apparatus for the Manufacture of Pyroligneous Acid from Sawdust."

The object of my invention is to adapt said apparatus to the automatic carbonization of sawdust for the purpose of obtaining gas for illuminating and other purposes, making also the charcoal available; to construct the parts thereof in a more durable manner, and to make the process more automatic.

The Halliday apparatus consists, essentially, of a bench of retorts, each of which is provided with a screw-conveyer, which gradually moves the sawdust along the same, and finally discharges it as charcoal, being fed into it from a hopper connected to it by a vertical tubular neck, also provided with a screw-conveyer.

In carbonizing sawdust for the production of gas a higher temperature has to be employed than the apparatus above referred to will bear. The consequence is that the conveyers in the retorts fail almost as soon as set to work, and if working for a little time the retorts soon give way. Nor does the apparatus work as automatically as desirable.

My invention consists in the construction and arrangement of parts for service, substantially as hereinafter specifically pointed out.

Figure 1 is a longitudinal vertical section through a retort-stack, showing one retort, with supply-hopper, vapor-main, and charcoal-main in cross-section. Fig. 2 is a front elevation of a retort-stack, representing a bench of five retorts. Fig. 3 is a longitudinal section of the charcoal-main, partly in elevation, showing hydraulic seal and mode of discharge. Fig. 4 is an enlarged cross-section of a retort, showing the tubular shaft of the screw-conveyer and the continuous fire-brick support of the retort. Fig. 5 is a diagram showing

the method of conveying the charcoal from the retort-house by the same conveyer that brings the sawdust to the retort. Fig. 6 is a modification of the manner of forming the hydraulic seal of the charcoal-main and discharging and removing the charcoal. Fig. 7 is another modification. Fig. 8 is another modification or plan of discharging the charcoal from the charcoal-main without the aid of a hydraulic seal, a solid body of charcoal being formed to prevent the exit of gas and the entrance of air.

A is a retort, of cast iron or fire-clay, set in a furnace or bench, in which it has practically a continuous support of fire-tiles F upon the piers F'.

A' is a mouth-piece at the front, projecting beyond the front wall, F'', of the furnace, and provided with a flanged trunk for the tubular feed-tube H', closed by a cover, a, with stuffing box a'.

B is the screw-conveyer having a hollow or tubular shaft, B', journaled at the front and rear in the stuffing-boxes a' and a'', and carrying the worm-wheel W, gearing in a worm, W', upon a shaft, S. In a bench of five retorts, which is the usual setting, the driving-gear of the shafts B' is preferably so arranged that one shaft S drives the entire number, said shaft being placed between the upper and lower row and carrying right and left handed worms W'. The tubular shaft B' is connected by means of a stuffing-box, b, to a water-supply pipe, p, taken from a main, P. The supply-pipe p may be provided with a regulating-cock, p'. The discharge from the tubular shaft B' at the rear of the retort may be open and flow in a trough, b', or the shaft may discharge in a branch pipe connected to the shaft B' by a stuffing-box similar to the arrangement in front.

Instead of using water as a cooling medium for the shaft B', a current of air may be forced through the same, either by pressure or suction; or, if the shaft be inclined and both ends be open, the air contained in the shaft is rarefied by the heat and a natural current is the result, which in some cases is sufficient to prevent the overheating of the shaft.

The sawdust is supplied to the retorts from the hopper H, which is filled by a chain conveyer, C, or in any convenient manner. The

casing of the chain conveyer is provided with slides *e*, controlling the discharge-apertures to regulate the supply to the hopper. The hopper is connected with each retort by a tubular connection, *H'*, containing a screw conveyer, *H''*, extending upward in the hopper, the shafts of these upright conveyers being suitably geared to a shaft, *S'*.

F are piers within the furnace, constructed with openings or flues *f* for the circulation of heat, and support a continuous or semi-continuous bridging, *F*, of fire-tiles, upon which the retorts are supported to prevent their sagging under the influence of heat.

15 *A''* is a mouth-piece at the rear of the retort, projecting beyond the rear furnace-wall, *F'''*, and provided with two flanged trunks to suitably connect the vapor main *M'* by the connecting-pipes *m'* and the charcoal-main *M* 20 by the connecting-pipe *m*. The mouth-piece is closed by a cover-plate, *a''*, provided with stuffing-box *a'''*, in which the conveyer-shaft *B'* is journaled.

The charcoal-main *M* is fitted with a screw-25 conveyer, *N*, to move the charcoal, and is provided at one end with a hydraulic seal, which may be constructed in various ways. For this purpose the end of the main *M* may have a mouth-piece, *O*, provided with stuffing-box *o* 30 to receive the conveyer-shaft, and having below a flanged angular trunk for connecting a short inclined pipe, *O'*, and to this an upwardly-inclined pipe, *O''*, fitted with a screw-conveyer, *N'*, the two pipes *O'* and *O''* forming 35 a *V*, partly filled with water or other suitable liquid to form a gas-seal. To maintain the water-level, either an independent supply may be used or the discharge from the tubular shafts *B'* may be utilized for that purpose. 40 The lower edge of the upper end of the open mouth of the discharge-pipe *O''* will act as an overflow and prevent an undue rise of the water-level forming the seal. (See Fig. 3.)

Instead of the arrangement just described, 45 the pipe *O''* may be dispensed with, as shown in Fig. 6, and the pipe *O'* may dip its open mouth in a trough, *T*, filled with water and discharge the charcoal therein, the latter being removed from the trough *T* by an endless-50 chain conveyer, *T'*, or other suitable means.

Another method of forming a hydraulic seal is shown in Fig. 7. Here the charcoal-main forms a downwardly-curved tube, *U*, filled with water and provided with an endless-chain 55 conveyer, *U'*, running over pulleys *u'* at each end and through said curved tube, and discharging into a trough or hopper, *u*.

Instead of employing special mechanical means of removing the charcoal from the water 60 forming the hydraulic gas seal, a current of water may be employed to perform said operation. The water, being supplied in a sufficiently copious quantity, will overflow at the proper exit provided for the same, and as the charcoal floats upon the same it is carried along with the current thus created and passes out with the overflow. The entrance of air into

the charcoal-main may also be prevented in a sufficiently practical manner by employing a plain charcoal-main, *M''*, which is not fitted its 70 entire length with a screw conveyer, *N''*, but having an open plain or contracted discharge-end, *m'*. In this discharge end the charcoal becomes very closely packed, and forms a tolerably-good gas-seal.

75 The charcoal may be discharged into wagons, as shown in Fig. 8, or, if wet, upon a heap to drain, and removed from thence by suitable mechanical conveyers. For this purpose the same endless-chain conveyer, *C*, that brings 80 the sawdust to the retort-house may be used to convey the charcoal out of it at the same time, inasmuch as the return-course will otherwise run empty. For this purpose the charcoal is elevated into the return chain-easing *C*, Fig. 5, by a suitable elevator, *E*, and discharged at any desired point along the conveyer.

The gaseous-products pass from the retort *A* through the mouth-piece *A'* and tubular 90 connections *m'* into the vapor-main *M'*, thence through a condenser, *D*, consisting of a series of horizontally-disposed pipes immersed in water or other cooling medium. In this condenser the condensable gases are thrown down 95 in the form of pyroligneous acid and tar, these products flowing out through a siphon. The vapors, thus partly purified, pass on through the scrubber and purifier to the gas-holder, being drawn through the condenser by a steam-100 jet ejector or other suitable exhauster.

I claim as my invention—

1. The combination of the sawdust-conveyer *C*, having discharge-openings with adjustable slides, the hopper *H*, tubular connections with the retorts *H'*, provided with screw conveyer extending into said hopper, retort *A*, with closed mouth-pieces and glands, a screw conveyer mounted on a hollow shaft, vapor-main *M'*, collecting and delivering the crude 110 vapors to the condenser *D*, and a charcoal-main, *M*, connected by tubular necks to the retort, said main being provided with a gas-seal and with means of moving the charcoal therein.

2. The charcoal-main *M*, receiving the carbonized sawdust from the rear of the retorts by tubular connections, said main provided with a screw conveyer, *N*, and with a hydraulic gas-seal consisting of a tubular downwardly-inclined extension, *O'*, and an upwardly-inclined tubular extension, *O''*, fitted with screw conveyer, the two inclined portions filled partly with water arranged to overflow at an orifice situated below the level of the main *M*.

125 3. The combination, with the retort *A*, having a screw feed device, a charcoal-main, *M*, receiving the carbonized sawdust from the retort and provided with a screw conveyer, a downwardly-inclined extension from the main and an upwardly-inclined discharging-tube having a screw conveyer, and a hydraulic seal for said discharge, substantially as described.

4. An automatic apparatus for producing

gas from sawdust, consisting of the sawdust-conveyer C, delivering in a hopper above the retorts, said hopper connected to the retorts A by tubular connections H', fitted with screw conveyor, the retorts A, set upon a bridging of the fire-tiles F, supported on piers F', and provided with screw conveyer having a tubular shaft passing through the ends of the retorts and adapted to pass a current of water or air, **15** **IC** a vapor main, M', placed above the rear ends of the retorts and connected thereto by tubular connections passing the gas to a condenser, D, and other apparatus for further treatment, a

charcoal-main, M, below the rear ends of the retorts and connected thereto by tubular connections, said main fitted with a screw conveyor, N, for moving the charcoal therein, and provided with a gas-seal, and delivering the charcoal into wagons or to an elevator, E, raising into the return-course C' of the sawdust- **20** conveyer.
